UNITED STATES PATENT OFFICE.

ALBERT T. BEMIS, OF LOUISVILLE, KENTUCKY.

DRYING-KILN.

SPECIFICATION forming part of Letters Patent No. 535,316, dated March 5, 1895.

Application filed August 31, 1891. Serial No. 404,325. (No model.)

To all whom it may concern:

Be it known that I, ALBERT T. BEMIS, a citizen of the United States, residing at Louisville, in the county of Jefferson and State of Kentucky, have invented certain new and useful Improvements in Drying-Kilns; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in drying-kilns; and it has for its object to provide means whereby a practically even temperature may be set up and maintained in the drying-chamber of a 20 kiln of the class commonly known as "progressive kilns," or that class of kilns in which the lumber, brick or other material to be dried is supplied to one end of the drying-chamber of the kiln, and during the process of drying 25 passes to the opposite end of the kiln, where it is removed, while the new stock is being continuously supplied at the entrance of the kiln.

In this class of kilns various methods have 30 been adopted for supplying a continuous current of heated air to the chamber of the kiln, such for instance as the air-blast, in which the current is maintained by means of an engine, fans, &c.; while in other instances the 35 current has been maintained by means of stacks of sufficient height to insure a uniform current. In still other instances it has been proposed to supply the requisite heat by arranging steam-pipes within a chamber beneath the floor of the kiln, the heat being permitted to enter the drying-chamber through 40 an inlet-passage provided in the floor at one end of the kiln. With all of these systems of kiln drying, a serious objection has been 45 found to exist, in the fact that the heated air depended upon for drying the lumber or other material, has had a tendency to rise to the upper portion of the chamber, and thus, while effectually drying the material within the upper portion of the chamber within a comparatively limited time, a much longer time has 50 been required to completely dry the lower

portions of the piles; thus necessitating that the entire charge of lumber or other material should be retained within the kiln for a much 55 longer time than would have been required to have dried it in the upper part of the chamber in order to secure a thorough drying of the lower portion of the charge.

I have discovered that by intersecting a 60 current of heated air admitted at one end of and passing longitudinally through the drying-chamber by heat radiated from a system of pipes arranged longitudinally of the chamber and located near the floor, the maximum 65 of radiated heat being in the vicinity of the minimum of heat in the longitudinal current, and vice versa, I can produce and maintain an even temperature throughout the entire chamber.

The invention is fully illustrated in the accompanying drawings, which, with the letters of reference marked thereon, form a part of this specification, like letters of reference indicating like parts throughout the several 75 views, and in which—

Figure 1, is a central longitudinal vertical section through a drying-kiln provided with my improvement. Fig. 2, is a horizontal section of the same.

Reference now being had to the details of the drawings by letter, A designates a drying-kiln of ordinary construction. The heated air enters the drying-chamber through the air-inlet passages B at one end, being heated by 85 the heater C, and forced into the drying-chamber by suitable fans D, and after traversing the length of the kiln it passes out through the outlet passage F at the other end of the chamber. This outlet passage F, is in the 90 form of a conduit secured to and movable with the vertically movable door F', which has in its lower end an opening f communicating with the interior of the chamber, as seen in Fig. 1.

G G represent tracks upon which the cars 95 or trucks containing the lumber or other material travel, these tracks extending the entire length of the apartment.

Suitably supported upon racks H, a few inches above the floor of the chamber and between the tracks G, are steam-pipes I, arranged longitudinally of the drying-chamber which are supplied by either heat or steam from any suitable source through the inlet-

pipe I', located at that end of the steam-pipes most remote from the air-inlet end of the chamber. After traversing the system of pipes the exhaust steam or air escapes through 5 the outlet-pipe I², located near the air-inlet end of the chamber.

From the foregoing it will be observed that where the temperature of the air-current is at its maximum it is intersected by the minimum 10 of radiated heat, and where the air-current is at its minimum temperature it is intersected by the maximum of radiated heat, and also that these relative conditions of temperature are maintained throughout the length of the 15 floor-pipes, with the result that in a short time after the heating of the chamber is commenced the temperature will be uniform in all parts of the drying-chamber.

It will be understood that the current of 20 heated air may be passed longitudinally through the drying-chamber by means other than the fan. For instance, an air-flue at the air-exit end of the kiln would cause the heated air to be drawn through the chamber.

Having thus described my invention, what 25 I claim to be new, and desire to secure by Letters Patent, is—

1. As a means for producing an even temperature within drying-kilns, an air-heating 30 apparatus, means for passing a current of heated air from said apparatus longitudinally through the drying-chamber, and a source of radiated heat within the chamber, near the floor, and independent of said air-heating apparatus, which source, when the kiln is in op- 35

eration, is hottest at that end of the chamber opposite the end at which the heated air enters.

2. In a kiln for drying lumber and other like materials, a close-floored drying-chamber 40 having one or more longitudinal car-tracks above the floor, a system of heating-pipes arranged longitudinally of each track and slightly above the floor, an air-heater independent of the heating-pipes, and means for 45 passing a current of air from said heater longitudinally through the drying-chamber, the air entering the chamber at the end nearest the outlet of the pipe-system and discharging at the end nearest the inlet of said system. 50

3. In a kiln for drying lumber and other like materials, a close-floored drying-chamber having one or more longitudinal car-tracks above the floor, a system of steam-pipes arranged longitudinally of each track and slightly above 55 the floor, the steam inlet and exhaust being at opposite ends of the chamber, an air-heater independent of the steam-pipes, and a fan for forcing a current of air from said heater longitudinally through the drying-chamber, the air being admitted at the end nearest the steam-exhaust and discharged at the end nearest the steam-inlet, substantially as described. 60

In testimony whereof I affix my signature in presence of two witnesses.

ALBERT T. BEMIS.
